UNITED STATES PATENT OFFICE.

JOHN T. LUCAS, OF MINNEAPOLIS, MINNESOTA, ASSIGNOR OF ONE-THIRD TO L. F. BLYLER AND ONE-THIRD TO A. H. RAND, OF MINNEAPOLIS, MINNESOTA.

WASHBOILER.

1,204,369.

Specification of Letters Patent.

Patented Nov. 7, 1916.

Application filed December 28, 1915. Serial No. 69,039.

To all whom it may concern:

Be it known that I, JOHN T. LUCAS, a citizen of the United States, resident of Minneapolis, county of Hennepin, State of Minnesota, have invented certain new and useful improvements in Washboilers, of which the following is a specification.

In the operation of an ordinary laundry gas stove, the products of combustion of the 10 gas are discharged into the room and even where the burner is close to the bottom of the boiler a poisonous gas is generated and inhaled by the person in the room, often with fatal results.

15 The object of my invention is to provide means in connection with a gas burner for supporting the boiler and conducting away the products of combustion and poisonous gases, and at the same time taking away the 20 steam from the boiler which is ordinarily discharged into the room and condenses on the floor or walls.

Other objects of the invention will appear from the following detailed description.

25 The invention consists generally in various constructions and combinations, all as hereinafter described and particularly pointed out in the claims.

In the accompanying drawings forming 30 part of this specification, Figure 1 is a vertical sectional view through a heater and boiler embodying my invention, Fig. 2 is a sectional view on the line $x-x$ of Fig. 1, Fig. 3 is a detail sectional view, showing the 35 manner of supporting the boiler at the top of the heater.

In the drawing, 2 represents the shell or jacket of the heater, made preferably of sheet metal, and supported upon suitable 40 legs 3. Brackets 4 are secured to said legs and support the plate 5, having a series of air intake openings 6 therein beneath a gas burner 7. This burner communicates through the jacket 2 with a gas supply pipe 45 8 and a nozzle 9 is mounted on an extension of the pipe 8 and arranged to project a flame through a port 10 in the wall of the jacket for the purpose of igniting the gas in the main burner, the flow of gas to the burner 50 and nozzle being controlled by valves 11 and 12.

At the top of the jacket a support for the boiler is provided, consisting, preferably, of an angle bar bent to a circular form and 55 having a horizontal flange 13 projecting into

the opening in the top of the jacket and its vertical flange secured to the side walls of the jacket. An elbow 14 is provided at the top of the jacket on one side and a pipe 15 communicates therewith and forms a vent 60 for the products of combustion of the burner, and for any gases which may be generated under the boiler.

16 represents a boiler, preferably cylindrical in form and having a cover 17 and an 65 outwardly rolled bead 18 at its upper edge that is adapted to rest on the horizontal flange 13 and support the boiler within the jacket. Handles 19 are preferably secured to the walls of the boiler and fit within 70 notches 20 in the flange 13. I prefer also to provide openings 21 in the upper walls of the boiler through which the steam from the boiling clothes may escape into the jacket.

The passage of the products of combustion around the boiler and through the vent pipe will create or establish a circulation and cause the steam flowing out through the openings 21 to immediately pass to the vent pipe, mingling with the products of 75 combustion therein. In this way I not only avoid the diffusion of the products of combustion and poisonous gases from the flame of the burner, but also remove the steam 80 of the boiling clothes, which usually is discharged into the room and condenses on the walls or any articles that may be in the room. I thus not only eliminate entirely 85 the dangerous gases produced at the burner, but also dispose of the steam which may 90 come from the boiling clothes or whatever may be contained in the boiler. Such a device may, of course, be used in connection 95 with a cooking utensil and still be within the scope of my invention.

Near the bottom of the boiler I prefer to provide a guard 22 bolted to the jacket and having an inwardly and downwardly extending flange 23 which terminates near the wall of the boiler and is adapted to direct 100 the gas flames downwardly and forwardly to a gap or opening that is provided between the ends of the guard. This guard compels the products of combustion to follow a circuitous path in the jacket and insures the 105 exposure of all portions of the boiler wall to the action of the burner flame. This deflector or guard 22 may be varied in length, according to the size of the passage desired for the products of combust 110

The device may be made in various sizes and in various ways the details of construction herein shown and described may be modified and still be within the scope of my 5 invention.

I claim as my invention:

1. The combination, with a sheet metal jacket having an open top and closed bottom, of a gas burner mounted on said bottom, said jacket having a flange encircling its open top and provided near said flange with an exhaust opening, a pipe connection therefor, a boiler fitting within said jacket and seated on said flange and forming a 15 substantially steam-tight joint therewith, the wall of said boiler having openings therein contiguous to said exhaust opening, for the purpose specified.
2. The combination, with a jacket having an open top and a gas burner mounted in the lower portion thereof, of a wash boiler fitting within said jacket, the walls of said boiler being spaced from the walls of said jacket, the upper walls of said jacket having 25 an exhaust opening and pipe connection therefor and said boiler having a cover and a passage through which the steam may escape into the space between said boiler and jacket for delivery to said exhaust 30 passage.

3. The combination, with a jacket and a burner mounted therein, of a boiler suspended within said jacket and spaced from said burner and the walls of the jacket, a deflector device interposed between said 35 boiler and the walls of said jacket and extending partially around the boiler, compelling the flames and products of combustion from the burner to follow a tortuous path around said boiler, a vent pipe leading 40 from said jacket, said boiler having discharge openings for the passage of steam to said vent pipe.

4. The combination, with a jacket and a burner mounted therein, of a boiler fitting 45 within the open top of said jacket and depending to a point adjacent said burner, the upper walls of said jacket having an exhaust opening and a pipe connection therefor, the walls of said boiler having 50 openings therein to allow the escape of steam into the space between said boiler and jacket, said jacket having means above said burner between it and said exhaust opening for deflecting the flames from said burner and compelling them to follow a 55 tortuous path around said boiler.

In witness whereof, I have hereunto set my hand this 23d day of December, 1915.

JOHN T. LUCAS.
